UNITED STATES PATENT OFFICE.

CHARLES W. GLIDDEN, OF LYNN, ASSIGNOR TO JAMES W. BROOKS,
TRUSTEE, OF CAMBRIDGE, MASSACHUSETTS.

HEEL-MAKING MACHINE.

SPECIFICATION forming part of Letters Patent No. 393,104, dated November 20, 1888.

Application filed June 25, 1888. Serial No. 278,146. (No model.)

To all whom it may concern:

Be it known that I, CHARLES W. GLIDDEN, of Lynn, in the county of Essex and State of Massachusetts, have invented an Improvement in 5 Heel-Making Machines, of which the following description, in connection with the accompanying drawings, is a specification, like letters on the drawings representing like parts.

This invention is intended as an improvement on the machine described in United States Patent No. 105,030, dated July 5, 1870, and has for its object to render the machine so improved more efficient for the work intended.

In the machine to be herein described the 15 dies are open at both ends. The plunger which acts to compress the heel in the die acts directly upon the heels. The awl-holding plate and the driver-plate are fitted into the stamp so as to be readily slid in and out of position. 20 The awls have co-operating with them a shipper-plate which is arrested as the stamp rises. The driver-plate is made adjustable vertically with relation to the stamp carrying it, and the driver-plate has co-operating with it a nail- 25 receiver, into which nails are discharged from a loader in usual manner when the driver-plate is elevated.

The especial features above enumerated as having been added to the machine referred to 30 will be made the subject of claims at the end of this specification.

Figure 1 is a top or plan view of a machine embodying my improvements; Fig. 2, a right-hand side elevation thereof; Fig. 3, a top or 35 plan view of the die-carrying cylinder or holder detached, together with the dies. Fig. 4 is a detail of the driver-plate, drivers, and nail-receiver; and Fig. 5, a detail to be referred to.

40 The bed A, its legs A', upright A², strengthening-web a, hanging support l, treadle T, spring T², receiving-table W for the heel-blank to be treated, the slide W', having the fork W², the follower-block F, to lift the heel-blank into

45 the dies to be described, the lever V to operate it, the main shaft L', fly-wheel N, pinion L, gear K, ratchet-wheel K', dog P', spring Q, swinging lever or stud S, rod m, tripping-lever Z, intermittently-rotating cylinder or die- 50 holder D, having openings or chambers for

the dies to be described, the shaft J, stamp-plunger B, stamp or head B' at its lower end, and face-plate I, are all substantially as in the patent referred to, where the like parts are designated by like letters.

55 Herein the dies b, carried by the cylinder or die-holder D, are made open at both ends, thus greatly cheapening the cost of their manufacture and enabling the tread end of the heel-blank to be acted upon directly by the presser 60 b', to be described, and to be freely entered by the awls, and especially by omitting the usual top to the dies various prickings may be employed with the same die.

The presser b' has its shank threaded, as at 65 b^x, and is screwed into a part of the stamp or head B', so that the presser may be adjusted vertically with relation to the said stamp or head which actuates it, in order that the presser may have just the desired extent of 70 throw to strike the tread end of the heel and force it down level with the top of the cylinder or holder D.

The pricking-awls 2 (any desired number) are arranged, as usual, in the awl-carrier 75 plate 3, the latter in accordance with my invention having its edges dovetailed or flanged to slide longitudinally out and in a groove of corresponding shape made in the stamp or head B', as shown in Fig. 2, so that the said plate is 80 readily removable when it is desired to introduce a plate having the awls differently arranged for a different pricking. A set-screw, 4, holds the plate 3 in place. The plate has rising from it a socket, d, which receives in it 85 the shank d' of the stripper d', through which the awls pass as they enter the heel to prick it. As the stamp or head rises to withdraw the awls, the upper end of the shank d' meets the adjustable stop 5, made as a screw screwed 90 into a lug, e, fixed to the frame-work, and is arrested thereby, so that the stripper stands while the awls continue to rise and are withdrawn from the heel-blank.

The tripping-lever Z at its inner end has 95 pivoted on it the usual stopping-dog, 12, for holding the cylinder D and dies b in position in the descent of the stamp.

The pivot 13, on which the dog 12 turns, is in my present invention extended upward, as 100

shown by dotted lines, Fig. 2, and receives upon it a rocker-lever consisting of a sleeve having an arm, f , of substantially the same shape as the end of the dog under it, and an arm or lug, f' . (Best shown in the detail, Fig. 5.)

The latch g , by which to move the cylinder D , it having a point to enter suitable notches in the said cylinder and having a handle by 10 which to move it, has an arc-shaped shoe, S , (see Fig. 2,) which enters a groove, 16, made in the bed A . This latch g has upon it an ear, upon which is pivoted a latch, 17, the inner end of which is beveled, as best shown in 15 Fig. 1, to act upon the arm f of the rocker-lever referred to as the latch g is moved fully to the right after having been moved in the opposite direction to effect the change of position of the dies, as provided for in the said 20 patent.

If it is not desired to release the slide-frame from the catch 21, then the latch 17 will be turned so as not to strike the arm f .

The stamp has a projection, h , (see Figs. 2 and 4,) provided with guides h' , in which slide the slide-rods h^2 , forming part of a frame, h^3 , to the lower end of which is secured the perforated nail-receiver h^4 , which receiver, when the parts are as in Figs. 2 and 4, is adjusted 25 to be filled with nails from a perforated nail-feeding block having a thin but movable bottom plate, as provided for in the said patent. The upper portion, h^5 , of the slide-frame enters a sleeve-like guide, h^6 , suitably attached 30 to and rising and falling with the plunger B , the said guide having within it a spring, 20, to normally throw the slide-frame down in the position Fig. 4 whenever the latch 21 is released from the head 19 of the said slide-frame, which is done whenever the latch 17 35 strikes the arm f , for then the socket shaft or sleeve to which the said arm is attached is turned sufficiently to cause the arm f' to meet the arm 24, attached to the rock-shaft 22, carrying the latch 21, the said rock-shaft having 40 its bearing in a sleeve, 23, fixed to the stamp B' .

The latch 21 is normally acted upon by a spring, 25, so that when the stamp is depressed the latch will catch under the head 19, ready 45 to lift the said nail-receiver when the stamp next rises, the lifting of the stamp and receiver permitting the cylinder and dies to be turned in usual manner.

The projection h referred to is slotted at m^6 50 to receive a nut, m' , into which is screwed the shank of the carrier m^2 , which is slotted or dovetailed to receive in it the dovetailed or flanged driver-plate m^3 , provided with drivers m^4 , the said plate being inserted in the carrier, 55 as described, so that it may readily be withdrawn when it is desired to place in the carrier a plate having drivers arranged to accommodate for a different prickings, the nail-receiver being also changeable.

60 In operation the heel-blank to be compressed, pricked, and loaded with nails will be moved by the fork W^2 into position imme-

diately above the follower-block F , when the operator, by the lever V' , will raise the follower and blank into that one of the dies which is directly over the follower-block, and then the operator will turn the cylinder or die-carrier D one step, bringing the said follower and die—the latter at that time being somewhat raised in the die-holder and having a blank partially driven into it—under the presser, the die-holder being stopped with the follower directly over a spring bed-piece supported upon a strong spring, the said bed-piece and spring not, however, being herein shown, because they are common to the said patent. With the die containing the blank in the position described, the stamp is thrown down, causing the presser to first act upon the elevated die containing the blank, the latter resting upon the “follower,” in turn resting upon the bed-piece, as stated, and presses the die down over upon and so as to compress the heel and force the latter into the die, the compression being continued until the upper end of the die and the tread end of the heel are brought into the same plane, and the die is forced down into its seat into the cylinder or die-holder, the follower within the die—as the die is brought down to its seat—acting to form a concavity in the seat end of the heel, as in the patent referred to. The heel having been compressed and the stamp lifted, the operator will give the cylinder another quarter-turn, bringing the compressed heel under the awls, which, as the stamp again descends, prick the heel at the desired points. The heel having been pricked, the stamp will be lifted, and as the stamp is lifted the shank d' of the stripper meets the stop 5, arresting the upward movement of the stripper d and permitting the awls d^2 to be drawn from the heels. During this latter operation the awls act to somewhat lift the die from the cylinder or die-holder; but, the awls having been completely withdrawn, the die drops back into its position, and the die-holder is again moved a quarter-turn until the pricked blank is brought into position under the nail-receiver, and as the operator moves the catch g back, as described, the latch 21 is operated to permit the nail-receiver to descend upon the pricked blank. The operator then, in usual manner, supplies the receiver with nails, and the stamp is again thrown down, causing the drivers m^4 carried by them to strike the ends of the nails then held in the receiver and drive them into the heel, after which the stamp is again raised, as described, and the cylinder is again rotated a quarter-turn, bringing the heel back into the position that it occupied when it was lifted into the die, when the said heel is discharged, as in the said patent, and another blank is inserted.

In the patent referred to, by reason of the die being closed at one end, great expense was entailed whenever it was desired to manufacture heel-blanks with different prickings, for then an entirely new die had to be made.

I am aware that the construction of said dies

was subsequently improved by casting into one end of the die a steel plate; but even with that form of die a new die had to be made for each pricking.

5 By leaving both ends of the die open it is possible to change the position of the awls and of the drivers to correspond with them according to any desired pricking, and the said awls will descend through the open bed of the die 10 into the blank, the plates carrying the awls and drivers being readily changeable on the machine.

I claim—

1. In a heel-making machine, a movable die-15 holder, D, and a series of independent dies, b, therein open at both ends, combined with a presser to act upon the die to compress the heel, substantially as described.

2. A movable die-holder, D, and a series of 20 independent dies, b, therein open at both ends, combined with a stamp, means to move it, and the presser b' and means, substantially as described, to adjust it, to operate substantially as described.

25 3. A movable die-holder, D, a series of removable dies, b, therein open at both ends, and a stamp, combined with an awl-carrying plate, 3, flanged or dovetailed to be slid out and in to a groove made in the said stamp, and means, 30 substantially as described, to hold the said plate in adjusted position, substantially as described.

4. A movable die-holder, D, a series of independent removable dies, b, therein open at 35 both ends, and a stamp, combined with an awl-carrying plate flanged or dovetailed to be slid out and in to a groove made in the said stamp, and with a stripper co-operating with the said awls, substantially as described.

40 5. A movable die-holder, a series of dies therein open at both ends, and a stamp, com-

bined with an awl-carrying plate flanged or dovetailed to be slid out and in to a groove made in the said stamp, and with a stripper co-operating with the said awls, and with a 45 stop to arrest the movement of the stripper, substantially as described.

6. The die-holder, a series of dies therein open at both ends, the stamp, means to move it, and the driver-carrier, combined with the 5c driver-holding plate and drivers, the said plate being flanged or dovetailed and adapted to be slid out and in to the said driver-carrier, substantially as described.

7. The die-holder and a series of dies therein, 55 combined with the stamp, the vertically-adjustable driver-carriers connected thereto, and with the removable driver-plate and drivers, to operate substantially as described.

8. The die-holder and a series of dies therein, 60 combined with the stamp, the vertically-adjustable driver-carrier connected thereto, and with the removable driver-plate and drivers, and with the slide-frame and the nail-receiver co-operating therewith, substantially as de- 65 scribed.

9. In a heel-making machine, the die to hold the heel to be loaded with nails, the stamp, the driver-carrier, the driver-plate and drivers, and the slide-frame and nail-receiver attached thereto, combined with the latch and with means to move the said latch to release the said slide-frame and permit the receiver to drop, substantially as described. 7c

In testimony whereof I have signed my name 75 this specification in the presence of two subscribing witnesses.

CHARLES W. GLIDDEN.
